UNITED STATES PATENT OFFICE.

JOSEPH WILSON, OF MONTROSE, PENNSYLVANIA.

DESIGN FOR A CUT-GLASS VESSEL.

SPECIFICATION forming part of Design No. 36,696, dated December 22, 1903.

Application filed November 25, 1903. Serial No. 182,688. Term of patent 7 years.

To all whom it may concern:

Be it known that I, JOSEPH WILSON, a citizen of the United States, residing at Montrose, Susquehanna county, Pennsylvania, have invented a certain new, original, and ornamental Design for a Cut-Glass Vessel, as shown in the accompanying drawings, wherein—

Figure 1 is a bottom plan view of a glass vessel having the ornamental cutting which comprises my new design. Fig. 2 is a side view of the same.

I claim—

The ornamental design for a cut-glass vessel, as herein shown.

In testimony whereof I affix my signature ¹⁵ in the presence of two witnesses.

JOSEPH WILSON.
